CLAIM

The ornamental design for a construction framing ruler, as shown and described.

DESCRIPTION

FIG. 1 is a perspective view of a construction framing ruler, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken line showing of indicia is included for the purpose of illustrating non-claimed subject matter and forms no part of the claimed design.
